(57) **CLAIM**

The ornamental design for a mixer base, as shown and described.

DESCRIPTION

FIG. 1 is a bottom, back and right side perspective view of a mixer base, showing our new design;

FIG. 2 is a top, front and left side perspective view thereof;

FIG. 3 is a left side view thereof;

FIG. 4 is a right side view thereof;

FIG. 5 is a front view thereof;

FIG. 6 is a back view thereof;

FIG. 7 is a top view thereof; and,

FIG. 8 is a bottom view thereof.

The dash-dash broken lines showing seams in FIGS. 1-6 show unclaimed portions of the mixer base and form no part of the claimed design.

The dot-dash broken lines in FIGS. 1-6 immediately adjacent to the claimed areas represent the boundaries of the design and form no part thereof.

None of the broken lines form any part of the claimed design.
